UNITED STATES PATENT OFFICE.

FRED EVANS, OF SUMMIT, NEW JERSEY, ASSIGNOR, BY MESNE ASSIGNMENTS, TO VOICES INCORPORATED, A CORPORATION OF DELAWARE.

TALKING-TOY MECHANISM.

Application filed March 21, 1923. Serial No. 626,499.

To all whom it may concern:

Be it known that I, FRED EVANS, a citizen of the United States, residing at Summit, county of Union, and State of New Jersey, have invented certain new and useful Improvements in a Talking-Toy Mechanism, of which the following is a specification.

This invention relates to sound producing devices, more particularly such as are used in toys, and it is herein intended to devise a sound producing mechanism for use in talking dolls.

The main object of the invention is to provide a new and improved sound producing mechanism of the class described which may not only be cheaply constructed, but which is rugged enough to withstand rough usage and which is efficient in operation. Further and more specific objects, features and advantages will more clearly appear from the detail description below.

In the accompanying drawing, wherein I have shown a preferred form of embodiment of my invention, Figure 1 shows a view of the device in partial vertical cross-section.

Figure 2 is a transverse cross-section on the line 2, 2 in Figure 1.

With reference now to the drawings wherein similar reference characters refer to similar parts throughout the views thereof, the reference character 1 designates a tubular casing, preferably formed of some light, cheap material such as cardboard or fibre and ordinarily formed in the shape of a cylinder. One end of this casing will be preferably closed by a head 2 and mounted intermediate the ends of the casing is a head 3 peripherally channelled.

Overlying this channel and held therein by a spring ring 4 is the marginal edge of a circumferentially creased tubular bellows 5, the upper end of this bellows being closed by a weighted disc or head 6. Preferably, the bellows will be constructed of some cheap air-proof material such as rubberized fabric, and the disc 6 will be made of cast lead. The head 3 is provided with an aperture 7, and on the outer face of the head 8, and overlying this aperture is a chamber 8, in one wall of which is mounted a reed pipe 9.

Positioned on the head 3 centrally thereof

is a chamber or passageway 10, this chamber lying in contact with the chamber 8 and so positioned that the reed 9 will open into the chamber 10. Thus air is adapted to pass through the reed pipe between the bellows and the chamber or passageway 10 to effect a sounding of the reed of the reed pipe. Chamber 10 is further provided with an orifice or opening 11 leading to the outside atmosphere. Attached to the weight 6 centrally thereof is a rod 12 which projects through the head 3 and into the chamber 10. Mounted on the end of this rod are spaced discs 13 and 14, these discs being provided with extending peripheral flanges or piston valve portions 15 and 16, made of a flexible material and being of such design as to lie closely in contact with the inner walls of the chamber 10.

It will be understood that devices of this character are ordinarily to be employed in connection with toys and the particular device here shown is designed for use in a talking doll, being commercially known as a "voice" for dolls. The operation of the device is as follows:

With the parts in the position indicated in Figure 1 and the weight 6 free to move under the influence of gravity so as to collapse the bellows 5, the downward movement of the weight will cause an expulsion of air from the interior of the bellows. This expelled air will pass through the reed and into that part of the chamber 10 which is defined between the flanges 15 and 16, being confined therein, inasmuch as the flanges are relatively air-tight.

Accordingly, since no air escapes to the atmosphere, little or no sound will be produced, but as the rod 12 moves down with the weight, the first flange 15 will eventually pass beyond the orifice 11, whereupon the air expelled from the interior of the bellows will be free to pass into the atmosphere, it being understood that the discs 14 and 15 are spaced such a distance apart as to permit the reed to be in communication with the atmosphere through the orifice 11 for a brief instant of time.

When the flange 15 has passed beyond the orifice 11 and the flange 16 beyond the reed pipe 9, the continued downward movement of the weight collapsing the bellows will

- force air through the reed into the chamber 10 above the flange 16, but eventually the flange 16, will ride beyond the orifice 11 whereupon the expelled air may pass into the atmosphere with the production of a second note. The flanges on the rod 12 are so spaced as to provide for two syllables rapidly enunciated, thus producing a "ma-ma" cry, the second syllable of the cry continuing as long as there is air to be expelled from the bellows. When the rod 12 has passed to its downward limit of travel, the sound ceases, whereupon the doll will be changed in position so that the parts may be moved by gravity to the position indicated in Figure 1, the weight being held at its outward limit of travel and being released therefrom so as to collapse the bellows only when the doll has been moved again.
- 20 It will be seen that I have provided a sound producing mechanism well adapted to attain the various aims and objects previously set forth. The device is made of a few inexpensive parts, readily assembled and easily mounted and concealed in position.

As many changes could be made in this construction without departing from the scope of the following claims, it is intended 30 that all matter contained in the above description or shown in the accompanying drawings shall be interpreted as illustrative only and not in a limiting sense.

Having thus described my invention, what 35 I claim as new and desire to secure by Letters Patent is:

1. A device of the class described having in combination a casing, a bellows therein having two heads, one being weighted and movable toward and from the other by gravity, a chamber secured to one of said heads and communicating with the interior of the bellows by a passage through the head, a second chamber secured to the same head and a reed pipe connecting said two chambers, said last mentioned chamber having a side opening to the atmosphere and a piston valve movable in said last mentioned chamber past said side opening to control the issuance of sound from the reed pipe to the atmosphere.

2. A device of the class described comprising, in combination, a casing, a head mounted intermediate the ends thereof, a bellows attached to one face of said head having a weight mounted in its free end, a chamber provided with a reed and in communication with the interior of said bellows, a cylindrical chamber having a side opening to the atmosphere and in communication with said reed, and means mounted on said weight and including a piston valve movable in said last named chamber past the said side opening to control the communication of said reed with said atmosphere.

3. A device of the class described com-

prising, in combination, a casing, a head mounted intermediate the ends thereof, a bellows attached to one face of said head having a weight mounted in its free end, a chamber provided with a reed and in communication with the interior of said bellows, a cylindrical chamber having a side opening to the atmosphere and in communication with said reed, a rod attached to said weight and extending into said last named chamber, and spaced piston valves mounted on the end of said rod and movable past the said side opening to control the flow of air through said reed to the atmosphere upon the collapse of said bellows.

4. A device of the class described comprising, in combination, a casing, a head mounted intermediate the ends thereof, a bellows attached to one face of said head having a weight mounted in its free end, a chamber provided with a reed and in communication with the interior of said bellows, a cylindrical chamber having a side opening to the atmosphere and in communication with said reed, a rod attached to said weight and extending through said head into the interior of said last named chamber and spaced valves provided with peripheral flanges lying in intimate contact with the interior walls of said chamber, said valves being so disposed on said rod as normally to cut off the communication of said reed with the atmosphere, but operable by the movement of said weight to place said reed successively in and out of communication with the atmosphere.

5. A device of the class described having in combination a bellows having two heads, one being weighted and movable toward and from the other by gravity, a chamber carried by one of said heads, a reed pipe through which air is adapted to pass between the bellows and said chamber, said chamber having a side opening to the atmosphere, and a piston valve actuated responsive to the operation of the bellows, and movable in said last mentioned chamber past said side opening to control the issuance of sound from the reed pipe.

6. A device of the class described having in combination a bellows having two heads, one being weighted and movable toward and from the other by gravity, a passageway carried by one of said heads, a reed pipe through which air is adapted to pass between said bellows and said passageway, said passageway having a side opening to the outside atmosphere, and a piston valve actuated responsive to the operation of the bellows, and slidably in said passageway past said side opening to control the issuance of sound from the reed pipe.

7. A device of the class described having in combination a bellows having two heads, one being weighted and movable toward and

from the other by gravity, a passageway carried by one of said heads, a reed pipe through which air is adapted to pass between said bellows and said passageway, said passageway having a side opening to the outside atmosphere, and a piston valve actuated responsive to the operation of the bellows, and having two transverse valve portions slideable in said passageway past said side opening to control the issuance of sound 10 from the reed pipe.

In testimony whereof, I affix my signature.

FRED EVANS.
